UNITED STATES PATENT OFFICE.

ARTHUR WILLIAM BEAUCHAMP AND EDGAR CHURCHILL DAVIDSON, OF SANDGATE, QUEENSLAND, AUSTRALIA.

INTERNAL-COMBUSTION ENGINE.

Application filed December 10, 1919, Serial No. 343,988. Renewed July 25, 1922. Serial No. 577,489.

To all whom it may concern:

Be it known that we, ARTHUR WILLIAM BEAUCHAMP and EDGAR CHURCHILL DAVIDSON, subjects of the King of Great Britain, residing at Sandgate, in the State of Queensland, Commonwealth of Australia, have invented certain new and useful Improvements in Internal-Combustion Engines, for which we have filed an application in Australia, dated Nov. 13, 1918, Serial Number 9264, and of which the following is a specification.

This invention relates to improvements in internal combustion engines, the object being to provide an improved arrangement of and means for controlling and operating the valves, also as the result of this improved arrangement an improved cylinder head or cover wherein the construction is greatly simplified and by means of which the dismantling or reconstruction of the engine is facilitated. Other advantages will be hereinafter set forth.

In carrying out our invention we fit the valves, which are spring, or otherwise, closed as desired in the cylinder head or cover. They are controlled by one or more inclined or cam faces which operate on the stems (fitted with antifriction rollers if desired) of the valves, and which are carried by or formed on gear wheels rotatable on the outside of the cylinder head or cover. These gear wheels mesh one with the other (or intermediate gear wheels may be provided between them) and they are driven from the main shaft by gearing or other suitable means. The ratio of gearing and the number of inclined or cam faces on the gear wheels are arranged to give the proper timing of the valves.

The cylinder head or cover is made in the one casting, the inlet and exhaust manifolds and passages being formed therein. The inlet to the inlet passage and the outlet from the exhaust passage coincide with openings in flanges on the cylinder casting, opposite which openings the fuel and exhaust pipes respectively are secured to the cylinder casting. The water pipes leading to and from the water jacket are connected to the cylinder casting and coincident openings are pro-

vided and suitably placed in the cylinder casting and cylinder head or cover so as to obtain a proper circulation. This arrangement of passages enables the cylinder head or cover to be removed without disturbing any of the pipes.

A protecting cover is provided over the gear wheels.

In order that the invention may be better understood we will now describe same with the aid of the accompanying drawings in which

Fig. 1 is a part front elevation (part in section).

Fig. 2 is a plan with cover removed. 65
Fig. 3 is a sectional plan.

Fig. 4 is a part side sectional elevation.

In carrying out our invention we fit the inlet and exhaust valve A A¹ in the cylinder head or cover B. These valves A A¹ are carried by the stems C, which are in turn secured at their upper ends to slides D slideable within (as shown) or on the outside of, guides D¹. In some cases we may use stems C only without the slides D. The upper end of the slides D (or stems C when such only are used) are fitted with antifriction rollers D² or they may have rounded tops. Suitable means are provided or the slides may be so formed 80 that they are prevented from turning round. The valves A, A¹ which are spring closed are operated by one or more bevelled projections or cams E on the under side of each of a number of spur wheels E¹. 85 These spur wheels E¹ mesh one with the other (or perhaps in some cases we may provide intermediate spur wheels between them). The spur wheels E¹ are driven by the pinion E² secured on the vertical shaft 90

F and mitre wheels G G¹ secured respectively on the shaft F and the crank shaft H. We may, in lieu of mitre wheels G G¹ use skew gear, a worm and worm wheel, or other form of drive. The ratio between the spur wheel E¹ and pinion E² is say four to one, and the gearing between the vertical shaft F and crank shaft H is say one to one.

The spur wheels E¹ and attendant parts are protected by a cover J. 100

The cylinder cover or head B is made in the one casting, the inlet and outlet manifolds K K¹ and passages L L¹ being formed therein with a wall L² between them, thus forming a "hot spot" manifold. The inlet to the inlet passage L and outlet from the exhaust passage L¹ coincide with holes M in the flanges M¹ M² on the cylinder N. The inlet and exhaust pipes P P¹ are secured to these flanges M¹ M². The water pipes leading to and from the water jackets Q are connected to the cylinder casting N at any suitable part and coincident openings Q² suitably placed in the cylinder casting N and cylinder head or cover B provide for the proper circulation of the water. This arrangement of inlet and exhaust pipes L L¹, water pipes and attendant parts permits of the cylinder head or cover being removed without disturbing any of the pipes.

In constructing engines in accordance with this invention we do not wish to bind ourselves to the details shown in the drawings, for instance, the spur wheels E¹ may be pivoted on the cylinder head or cover B instead of pivoted from the cover J.

In operation it will be seen that half a revolution of the spur wheel E¹ (with two cams E thereon) to two revolutions of the crank shaft H is equivalent to the present practice of one revolution of the cam shaft to two of the crank shaft H. The operation of our engine is otherwise much the same as those at present in use, so that it is not necessary to enter into details. The following points may, however, be set forth as showing the advantages gained by our invention over engines at present on the market, and as indicating an improved operation.

1. The spur wheels E¹ with cam faces E operating the valves A A¹ direct, dispense with the cam shaft, valve tappets, push rods and rocker arms with their respective guide bearings, etc., thus eliminating all lost motion between the cams and valves. This tends to make the valve operation more silent. 2. The valve operating gear, being driven at $\frac{1}{2}$ instead of $\frac{1}{3}$ engine speed, further tends to make the valve operation more silent. 3. The whole of the valve operating gear being situated in or on the cylinder head B the removal of one cover J exposes all working parts for inspection. 4. All spur wheels E¹ for operating valves A A¹ are identical and the cam faces E on same being removable are cheaper to manufacture and easily replaced if worn, whereas the cam shaft in present use is expensive to manufacture and should, as sometimes happens, one cam face wear more than another, the whole cam shaft has to be renewed. 5. This arrangement of valves A A¹ and cams E provides for a quicker opening and closing of the valves allowing them to remain fully

open for about $\frac{1}{3}$ of their period preventing any tendency to "wire drawing" the gases. 6. The slides D on the valve stems C besides making an efficient guide for the valves A A¹ form dashpots which tend to prevent the valves A A¹ bouncing. 7. Much simplified cylinder casting, no provision having to be made for timing gear cam shaft and valve tappets. 8. Although the cylinder head B is perhaps a more complicated casting than some at present used, this is more than compensated for by—(a) doing away with the separate inlet and exhaust manifolds K K¹ and their fixings, (b) the before mentioned simplification of the cylinder casting N, (c) a good "hotspot" L² being formed between the exhaust and inlet manifolds K K¹ enabling inferior fuels to be used, (d) more efficient cooling of valve stems C and spark plugs, (e) the cylinder head B being removable without interfering with the carburetor or the exhaust and water pipes. 9. Clean outline of engine with no moving parts exposed but all accessible. 10. A cheaper engine to manufacture. 11. A cheaper engine to maintain.

Having now particularly described and ascertained the nature of our said invention and in what manner the same is to be performed we declare that what we claim is:

1. In combination, cylinders provided at opposite sides with apertured flanges connected to an intake pipe and an exhaust pipe, a detachable head for said cylinders provided with a centrally disposed horizontal compartment divided longitudinally by a wall into an inlet chamber and an exhaust chamber which communicate with the interiors of the cylinders, and pipes connected to said chambers and having horizontally disposed flanges detachably engaging the flanges of the cylinders.

2. An internal combustion engine including a plurality of cylinders arranged side by side, a head casting adapted to cover the upper ends of both cylinders and provided with a plurality of T-shaped passageways, a dividing wall between said passageways extending in a plane intersecting the axes of the cylinders, a valve port connecting each of said passageways with each of said cylinders, reciprocable valves cooperating with said ports to admit an explosive charge to the cylinders and to discharge the exhaust gases from the cylinders, a plurality of meshing gear wheels mounted above said head and rotatable about axes which are coaxial with the axes of the cylinders, cams provided on the undersides of said gear wheels and engageable with said valves for actuating the same, a crank shaft for the engine, and means connecting said crank shaft with one of said gear wheels for actuating said gear wheels from the crank shaft.

3. In an internal combination of the kind defined by claim 2, a cover plate mounted on the head, and stub shafts carried by said cover plate and functioning as axes for said 5 gear wheels.

Dated this tenth day of November, A. D. 1919.

In testimony whereof we affix our signatures in the presence of two witnesses.

ARTHUR WILLIAM BEAUCHAMP.
EDGAR CHURCHILL DAVIDSON.
